BLANK FOR A MAP OR SIMILAR ARTICLE

Benjamin Klein, New York, N. Y.

Application July 27, 1951, Serial No. 16,049

Term of patent 3½ years

(Cl. D25—1)

To all whom it may concern:

Be it known that I, Benjamin Klein, a citizen of the United States, residing at 3930 Forty Seventh Street, city of New York, in the county of Queens and State of New York, have invented a new, original, and ornamental Design for a Blank for a Map or Similar Article, of which the following is a specification, reference being had to the accompanying drawing, forming part thereof.

The figure is a plan view of a blank for a map or similar article, showing my new design, the same being of no appreciable thickness.

I claim:

The ornamental design for a blank for a map or similar article, substantially as shown and described.

BENJAMIN KLEIN.
